CHARGING COKE OVENS

Carl Otto, Manhasset, N. Y., assignor to Fuel Refining Corporation, New York, N. Y., a corporation of Delaware

Application May 19, 1942, Serial No. 443,590

4 Claims. (Cl. 202—262)

The general object of the present invention is to provide an improved method of, and improved means for charging comminuted coal to be coked into the deep, narrow, horizontally elongated retorts or coking chambers of the general type now employed in the manufacture of coke suitable for metallurgical use. Each such oven is customarily provided with a plurality of roof openings, or charging holes, distributed along the length of the retort and through which the coal to be coked is allowed to fall in the oven charging operation.

Modern coke ovens or retorts of the above mentioned type customarily have a depth varying from about 10 to 15 feet and have a roof thickness of the order of three feet. Furthermore, the coal customarily acquires appreciable down velocity before it enters the upper end of the charging hole. In consequence, the mass of coal within the oven chamber and constituting the charge to be coked, is compacted and has its density increased by the impact of the falling coal against the surface of the charge which is being formed. The increase in density of the charge due to the impact of the falling coal particles which becomes a part of the charge, is highly objectionable under some conditions.

I have found that the increase in the density of the coal charged thus produced, is especially objectionable in the carbonization of low volatile, expanding coals, and my present invention in its more limited aspects constitutes an improved method of, and improved apparatus for coking such coals. As explained in my copending application Serial No. 433,119, filed March 3, 1942, in coking low volatile, expanding coal, the tendency of the coal charge to expand sufficiently to cause distortion of the walls of the chamber in which the mass is coked may be substantially eliminated by so forming the coal charge as to increase its aggregate void space so that its coal content per cubic foot will not weigh more than about 42 pounds.

In my above mentioned patent application I have disclosed a special method of preparing low volatile, expanding coal for coking, which consists in adding sufficient water to the comminuted coal to make the latter crumbly and then stirring or otherwise aggregating the crumbly coal mass to increase the aggregate void space in the mass, so that the weight per cubic foot of the coal in the charge will not exceed the desired amount. When the density of the coal charge is thus reduced, the tendency to objectionable expansion

of the charge in the coking operation, and the resultant distortion of the coking chamber walls is substantially eliminated.

When the crumbly coal prepared in accordance with the method of my prior application is allowed to fall freely through the charging holes in the roof of a deep coking chamber, the impact of the crumbly coal aggregates against the charge building up in the lower portion of the oven, tends to diminish the aggregate void space in the charge and thus neutralize the advantageous effect of the special treatment previously given the coal to increase its aggregate void space.

A specific object of the present invention is to prevent or minimize the tendency to an increase in the density of the charge formed in a coking chamber having charging holes in its roof, by retarding the velocity of the coal falling into the chamber through said holes. By suitably retarding the velocity of the falling coal, I am able to obtain substantially full advantage of the method disclosed in my above mentioned application for increasing the aggregate void space in the charge, and in some cases I am able to obtain a suitably high aggregate void space in a charge of comminuted low volatile, expanding coal which is substantially dry and contains much less moisture than is required to give the coal the crumbly characteristics contemplated in my prior application. The present invention comprises means which may take various forms, for keeping the velocity of the coal suitably low as it moves by gravitational action down into a coking chamber, through the charging holes in its roof.

The various features of novelty which characterize my invention are pointed out with particularity in the claims annexed to and forming a part of this specification. For a better understanding of the invention, however, its advantages, and specific objects attained with its use, reference should be had to the accompanying drawings and descriptive matter in which I have illustrated and described a preferred embodiment of the invention.

45 Of the drawings:

Fig. 1 is a somewhat diagrammatic elevation of a coal charging lorry and a portion of a subjacent coking oven battery shown in transverse section;

Fig. 2 is a view taken similarly to Fig. 1, but on a larger scale and showing a portion only of the apparatus shown in Fig. 1;

Fig. 3 is a section on the line 3—3 of Fig. 2;

Fig. 4 is an elevation of a modified form of retarder;

Fig. 5 is a sectional elevation through a third form of retarder;

Fig. 6 is a transverse section on the line 6—6 of Fig. 5; and

Fig. 7 is a sectional elevation taken similarly to Fig. 5 but with the retarder in its collapsed or minimum length condition.

In the drawings and referring first to the form of invention shown in Figs. 1, 2 and 3, A designates a horizontal coke oven battery of the usual type comprising transversely extending coke oven chambers B with charging holes B' in the roofs of said chambers. Mounted on the top of the battery structure are the usual lorry car track rails C' extending longitudinally of the battery and engaged by the flanged wheels C' of the lorry car C. The latter comprises as many hoppers D, usually about four, as there are charging holes B' in the roof of each channel B. The lower portion of the hopper D shown, diminishes in cross section, as it approaches the battery roof, and its lower end terminates in an outlet D'.

For the purposes of the present invention the lorry preferably includes a discharger of feeder E associated with each hopper D to move coal laterally from the outlet D' into a corresponding stand pipe F included in the lorry structure and having its lower end above and in register with the corresponding charging hole B' in the oven charging operation. The discharger E shown is of the vibratory type and form disclosed and claimed in my copending vibratory motor application Serial No. 367,349, filed November 27, 1940, and comprises a discharger trough E' slightly inclined to the horizontal with its open discharge end E' lower than its closed end E³. As shown the discharger E is resiliently suspended from the hopper D through suspension elements E⁴, each of which includes a tension link E⁵, and includes a power or motor element E comprising a plurality of stiff metal springs or vibrator bars E⁶ clamped at their ends in the frame of the element, and having their central portions connected through a suitable yoke or clamp structure to an armature E⁷. The latter is attracted, and the spring bars E⁶ are thereby deflected, by the energization of an electro-magnet E⁸. The energizing current for each electro-magnet may be an alternating current, or it may be a pulsating current comprising alternating current and direct current components. In general, the discharger vibration frequency will be double the alternating current frequency if the magnet E⁸ is energized by alternating current, and will be the same as the alternating current frequency if the magnet E⁸ is energized by a pulsating or mixed current comprising both alternating and direct current constituents. The effective discharge capacity of the vibrator may be varied by varying the strength of the current energizing its magnet.

The open discharge end E' of the discharge trough E¹ extends into a stand pipe F through an opening F' in the wall of the latter and the stand pipe F serves as a means for guiding the coal discharged from the trough into the charging opening, and as a smoke pipe for carrying the distillation and burning gases issuing from the charging holes during the charging operation, to a level well above the top of the battery. As shown, the stand pipe F also serves as a housing for a coal retarding element which in accordance with the present invention extends into the oven chamber B through the charging hole B' during the charging operation and may

take various forms. In the form shown in Figs. 2 and 3, the retarding element G comprises two vertical bar-like body portions displaced from one another in the direction of the length of the oven chamber and connected by a set of integral inclined baffles G¹ at the side of the retarder adjacent the discharger E, and a second set of inclined baffles G² at the opposite side of the retarder. The baffles G¹ which are spaced apart vertically, are in staggered relation with the similarly vertically displaced baffles G². Each of the baffles G¹ and G² is inclined to direct coal falling on it away from the side of the retarder at which it is located and toward the side of the retarder at which the other set of the baffles is located. The retarder G may well be a one piece iron or refractory metallic casting.

The retarder G is suspended and adjusted vertically by a suitable suspension mechanism which in the form shown, comprises a cable H running over guide pulleys H¹ at the top of the lorry and having one depending end attached to a connector part G³ of the retarder G. The other end of the cable H is connected to the winding drum 20 of a motor actuated winch H², mounted on the lorry.

In the preferred mode of using apparatus of the type shown in Figs. 1, 2 and 3 in charging a coke oven chamber in accordance with the present invention, coal is simultaneously fed at suitable relative rates through the different oven charging holes B' in the roof of the oven chamber which usually has not less than three and not more than five such holes suitably distributed 30 along its length. Preparatory to the initial discharge of coal into an oven chamber through each charging hole, the corresponding retarder G is lowered into the hole until its lower end is in suitable proximity to the retort floor, and as the 35 charging operation proceeds the retarding device is progressively raised. In some cases the bottom of each retarder may be kept above the top surface of the charge being formed throughout the charging operation. In other cases, however, the 40 retarder may be kept in the charge throughout the major portion of the charging operation. In such case, when the retarder is eventually raised, its movement through the charge has a certain 45 charge leveling effect and minimizes the tendency 50 of the portion of the charge directly beneath the corresponding charging hole B' to be more densely compacted than are the portions of the charge further away from the axis of that charging hole. At the end of, or during the final portion of the 55 charging operation, the retarder G is raised to lift its lower end out of the charging hole B' and the oven roof structure.

As will be apparent, with the retarder shaped and proportioned as shown in Figs. 1, 2 and 3, practically every particle of coal passing down into the oven chamber will impinge against one at least of the baffles G¹ and G² which is at a level somewhat below the roof of the oven chamber; and some of the coal particles will successively engage a plurality of said baffles at successively lower levels. The effect of each such engagement of a coal particle with a baffle G¹ or G² is to sharply reduce the vertical velocity of the particle. Apparatus of the type and form shown 60 in Figs. 1, 2 and 3 is thus adapted to substantially reduce the tendency of the coal falling on the top surface of the charge being formed to increase the density of the charge by impact action.

75 In Fig. 4 I have illustrated a modified form of

retarder GA which may also well be a one piece iron or refractory metallic alloy casting. The retarder GA comprises a central shaft portion G⁵ terminating at its upper end in an eye G⁶ for engagement by the cable H, and baffle arms G⁷ extending away from the central shaft portion of the retarder at different levels and retarding the down falling coal in the same manner as do the baffles G¹ and G² of the retarder G. As shown, each arm G⁷ is inclined upwardly away from the horizontal and outwardly away from the shaft portion of the retarder. Furthermore, each baffle G⁷ preferably increases in width as its distance from the central portion of the retarder increases and has its upper surface in skew relation to the retarder shaft portion G⁵ so as to minimize the tendency of coal falling on the baffle to lodge and be retained thereon. The upper surface of each baffle arm G⁷ may well be a portion of a surface extending helically about the shaft portion G⁵.

In Figs. 5 and 6 I have illustrated another form of retarder comprising a series of generally similar telescopic sections GB, GC and GD. As shown each of said sections is a cut away tubular part having an inclined bottom baffle G¹⁰ at one side and an oppositely inclined baffle G¹¹ at its opposite side and at a higher level. The section GB carries a pin G¹² working in a vertical slot G¹³ in the peripheral wall of the member GC to limit the relative movement of the two sections in the direction to elongate the retarder. The members GC and GD have a similar pin and slot connection. As shown, the inner element GB is provided with an out turned portion G¹⁵ at its upper end which is adapted to engage a shoulder portion F⁵ of the corresponding stand pipe FA and thereby limit the down movement of the section GB. The lower section GD is shown as formed with a transverse bar portion G¹⁶ extending diametrically across the hollow interior of said section to which the cable H or other suspension device is attached. The other sections GB and GC are formed with vertically extending slots G¹⁷ each open at its lower end and each receiving the transverse bar G¹⁶ when the retarder sections GB, GC and GD are nested together to give the retarder its minimum length as shown in Fig. 7.

Such retarding elements as are illustrated by way of example in the accompanying drawings are capable of effecting a reduction in the velocity of impact of the charge forming coal particles against the top surface of the charge being formed, and of thereby materially reducing the density of the charge formed. The density decreasing effect of such retarding means is especially important in charging oven chambers with coal in the form of crumbly aggregates produced when low volatile, expanding coal is prepared for charging in accordance with the method disclosed in my above mentioned copending application Serial No. 433,119.

In preparing low volatile, expanding coal for coking in accordance with the method of the last mentioned application, the coal is subdivided to such fineness that all of it will pass through a No. 7 (micron 2830) screen, and 80% of it will pass through a No. 10 (2000 micron) screen, and at least 40% of it will pass through a No. 40 (420 micron) screen. The amount of water in the wet coal mass needed to give the latter its characteristic crumbly condition, increases with the fineness of the coal, and its weight may vary between 8 to 20% of the weight of the coal.

To facilitate the thorough wetting of the coal, some suitable wetting material or agent may be used, for example, soap may be added to the water, or use may be made of some commercial wetting agent now on the market, such as "Wetanol." The coal may be given the desired water content during or preparatory to the final subdivision of the coal. When the final subdivision of the coal is effected in a hammer mill, the latter subjects the coal to the stirring action or agitation necessary to make the aggregate air and wafer filled spaces between the coal particles twenty per cent or so greater than the aggregate air filled void spaces in an equal volume of dry coal of the same composition and fineness. In ordinary practice the weight of the coal in the wet coal mass charge in the oven chamber should be about forty-two pounds per cubic foot. Low volatile, expanding coal prepared for coking in the manner described may be coked in ovens of standard type used in the manufacture of metallurgical coke and operated within the temperature and coking time ranges customarily employed in the production of metallurgical coke by so-called high temperature carbonization of ordinary good coking coal having a substantially higher volatile content. Expanding low volatile coal prepared as described and charged into coking chambers in accordance with the present invention and coked in the manner customary in the production of metallurgical coke, does not subject the walls of the coking chamber in which it is coked to objectionable stresses.

The coking characteristics of coal prepared for coking in the manner above described and the strength of the coke produced, may advantageously be improved in some cases by adding to the coal from two to five per cent by weight of finely subdivided coke or coke breeze, and further improvement in the coke produced may be obtained in some cases by adding to the above described coal and coke mixture an amount of finely subdivided pitch equal in weight to about five or six per cent of the weight of the coke in the mixture. When coke and pitch are thus added to the coal, the coke may be initially mixed with the pitch and the mixture may then be heated to more or less completely melt the pitch and thereby agglomerate the mixture, after which the agglomerated mixture may then be ground to such fineness that all, or practically all of it will pass a No. 40 (420 micron) screen.

When coal thus prepared for charging in accordance with the method of my copending application, is charged into a coking chamber in the usual manner, the aggregate or agglomerated masses of crumbly coal having an average size much greater than the average size of the individual coal particles, impact against the previously formed portion of the charge, with the undesirable result of eliminating an appreciable portion of the aggregate void space in the charge which may be obtained by retarding the falling movements of the crumbly coal aggregates into the oven chamber, in accordance with the present invention.

While in accordance with the provisions of the statutes, I have illustrated and described the best forms of embodiment of my invention now known to me, it will be apparent to those skilled in the art that changes may be made in the forms of the apparatus disclosed without departing from the spirit of my invention, as set forth in the appended claims and that in some cases certain features of my invention may be used to advan-

gage without a corresponding use of other features.

Having now described my invention, what I claim as new and desire to secure by Letters Patent is:

1. Means for charging coal into a coking chamber through an opening in the top wall of the latter, comprising means for passing a stream of coal downward through said opening, coal retarding means extending through said opening into position to be engaged by and thereby decrease the downflow velocity of the coal falling through said opening, and means for raising said retarding means as the depth of the charge of coal being formed increases.

2. A coal lorry for charging horizontal coke oven battery coking chambers each formed with one or more top charging holes, comprising in combination a discharge spout adapted to register with a corresponding charging hole, a coal

hopper laterally displaced from said spout, means for moving coal from said hopper into said spout and a retarding element mounted on said lorry for vertical adjustment between an upper position in which it is above the charging hole top level, and a lower position in which it extends down into a chamber being charged through the corresponding top charging hole and said spout and is adapted to impede and reduce the downflow velocity of the coal falling into the chamber through said top charging hole.

3. A coal lorry combination as specified in claim 2, in which said retarding element comprises oppositely inclined baffles at different levels.

4. A coal lorry combination as specified in claim 2 in which said retarding element comprises sections telescopically adjustable to vary the length of said element.

CARL OTTO.
